US00D757295S

(12) **United States Design Patent**
Benarieh et al.

(10) **Patent No.:** **US D757,295 S**
(45) **Date of Patent:** **** May 24, 2016**

(54) **ELECTROBLOTTING APPARATUS**4,757,022 A * 7/1988 Shults A61B 5/1486
204/403.05(71) Applicant: **LIFE TECHNOLOGIES
CORPORATION**, Carlsbad, CA (US)4,840,714 A 6/1989 Littlehales
4,889,606 A 12/1989 Dyson et al.
5,013,420 A 5/1991 Schuette
5,173,159 A 12/1992 Dutertre
5,256,772 A 10/1993 Ohtomo
5,273,906 A 12/1993 Shultz et al.(72) Inventors: **Ronen Benarieh**, Givat brener (IL);
Raviv Lifshitz, Tel Aviv (IL)(73) Assignee: **Life Technologies Corporation**,
Carlsbad, CA (US)

(Continued)

(**) Term: **15 Years**

23/046; G01N 27/4473The ornamental design for an electroblotting apparatus, as
shown and described.

See application file for complete search history.

DESCRIPTION

(56)

References CitedFIG. 1 is a perspective view of an electroblotting apparatus;
FIG. 2 is a right side view thereof;

U.S. PATENT DOCUMENTS

FIG. 3 is a left side view thereof;

3,879,280 A 4/1975 Peterson et al.
4,139,440 A 2/1979 Chrambach et al.
4,452,901 A 6/1984 Gordon et al.
4,589,965 A 5/1986 Kreisher
4,622,124 A 11/1986 Kreisher et al.

FIG. 4 is a front view thereof;

FIG. 5 is a back view thereof;

FIG. 6 is a top view thereof; and,

FIG. 7 is a bottom view thereof.

The broken lines shown represent unclaimed subject matter
and form no part of the claimed design.**1 Claim, 7 Drawing Sheets**(56)
